DENTAL BRUSH

Daniel R. Coleman, Roselle Park, N. J.

Application September 26, 1936, Serial No. 102,719

2 Claims. (Cl. 15—188)

This invention is a sanitary dental brush comprising a brush stock of rubber having wedge shaped teeth molded integrally therewith and arranged in longitudinal and transverse rows 5 along one side of the stock, to efficiently clean and polish the teeth and massage the gums.

So called rubber tooth brushes have heretofore been suggested, but have been open to certain objections. For example, they have either 10 been too flabby or too hard to carry out their functions in an efficient or satisfactory way. I have overcome these objections by making the teeth of wedge shape so that they terminate in relatively fine straight transverse edges and by 15 thus forming these teeth upon a hollow brush stock normally of a relatively small size but possessing such inherent elasticity and resiliency that the stock may be distended by forcing a handle into its hollow confines to place all portions 20 of the stock, as well as the base portions of the several teeth, under considerable stress or tension. When the teeth are stressed in this manner, the base of each tooth is increased in the direction of the length of the brush and is 25 placed under tension which materially stiffens the whole tooth, while tending to hold it in a state of equilibrium. Any pressure against the 30 end of such a tooth may cause the tooth to yield but as soon as the pressure is released it will return to its initial position under its original stress.

Experience with a brush of this kind has shown that it possesses unusual cleaning and 35 massaging properties. It produces a sort of kneading effect which is particularly efficient for its intended purpose.

An important feature of the invention consists in the use of a handle adapted to normally 40 occupy the interior of the stock to distend the same and which handle is preferably provided with a metal tang which distends the stock for the purposes stated.

Features of the invention, other than those 45 adverted to, will be apparent from the herein- after detailed description and claims, when read in conjunction with the accompanying drawing.

The accompanying drawing illustrates one 50 practical embodiment of the invention, but the construction therein shown is to be understood as illustrative, only, and not as defining the limits of the invention.

Figure 1 is a longitudinal section through a brush embodying the present invention, showing 55 the handle detached.

Figure 2 is a like view, but showing the parts assembled.

Figure 3 shows, in full lines, a top plan view of the brush stock shown in Figure 1 and, in dotted lines, the stock is shown as it is distended 5 after the handle has been associated therewith. The handle is also shown in this figure in dotted lines.

Figure 4 is a section on line 4—4 of Figure 1.

Figure 5 is a section on line 5—5 of Figure 2. 10

Figure 6 is a greatly enlarged view of three teeth showing the manner in which these teeth are deformed and stressed when the tang of the handle is introduced into the hollow stock of 15 the brush.

The brush of the present invention comprises, generally speaking, a stock 1, and a handle 2, the latter of which is provided with a tang 3. The stock is made of resilient, yieldable material, such as vulcanized rubber and is provided 20 on one face with longitudinal and transverse rows of closely spaced apart teeth 4. These teeth are molded integral with the stock and are of substantially wedge shape, being tapered from a relatively broad base to a relatively fine transverse edge. In their initial molded condition, 25 they are approximately three times as high as the distance across their bases, while the lateral edges of the teeth are parallel. They extend in close succession longitudinally of the stock and 30 are arranged side by side with intervening straight-sided channels 5.

The stock is made hollow to provide therein a cavity 6 having relatively thin walls and into this cavity is adapted to be received the tang 35 3 of the handle. The tang is made somewhat longer than the length of the cavity and also of somewhat greater width, but the primary consideration is that it be made longer than the length of the cavity, the transverse construction 40 being mainly to insure proper gripping between these parts to hold them in predetermined relation after they are assembled.

It is of course possible to make the tang as an integral part of the handle but, as considerable strength is desired in a tang and metal handles are not popular, I preferably make the handle of some composition material and embed one end of a metal tang therein. I have found that aluminum makes a very satisfactory tang. 50 It is light, sufficiently strong and does not corrode.

After the brush and handle have been independently made, they are assembled by forcing the tang 3 of the handle into the cavity 6 of 55

the brush stock in such a way that the brush stock is stretched out or elongated sufficiently to cover the tang. When this is done, the cross section of the hollow stock is distended and placed 5 under considerable tension, thereby causing the tang to be firmly gripped by the stock in such a way that the stock will not recede longitudinally of the tang, but will be maintained in its distended condition. When the stock is longitudinally distended, however, it will be apparent 10 that the bases of the teeth adjacent the stock must also be distended or broadened out.

This is graphically illustrated in Figure 6, where I have shown three teeth. The full line 15 position shows the teeth as molded, whereas the dotted line positions show the teeth after they have been distended or stressed through longitudinal stretching of the stock. This stretching will occur as indicated by the arrows in this figure and will cause an increase in the length of 20 the base of each tooth, which will place said teeth under a condition of stable equilibrium, so that they may be graphically said to be "alive." They appear to be somewhat stiffened by this 25 operation, yet their resiliency appears to be appreciably increased. When drawn across a surface of the gums or the human dentures, they exert a kneading action highly conducive to 30 cleansing of the human dentures and effect a very pleasing and highly efficient massage of the gums. Their operation is pronouncedly different 35 from the dead, flabby action of the ordinary rubber bristles or projections heretofore employed in connection with rubber tooth brushes. The teeth of the brush of this invention have a live whip, with sufficient stiffness to operate properly upon the dentures and gums but not 40 sufficiently stiff to cause any harm thereto.

The rubber teeth, stressed in the manner 45 stated, have an action which simulates the muscular action of the human fingers in giving massage treatment to the gums and this has long been advocated and admittedly gives the most satisfactory results. The present invention has this finger action and is at the same time more sanitary than direct finger application.

The foregoing detailed description sets forth the invention in its preferred practical form, but the invention is to be understood as fully commensurate with the appended claims.

Having thus fully described the invention, 5 what I claim as new and desire to secure by Letters Patent is:

1. A dental brush comprising a handle having a tang, in combination with a hollow resilient and flexible stock having a cavity extending longitudinally thereto from one end thereof to a point adjacent the opposite end of the stock, with longitudinally adjacent rows of juxtaposed wedge shaped teeth integral with one side of the stock, the cavity in said stock being normally of 15 lesser length than the length of the tang and of lesser cross sectional area than the tang and the stock being drawn upon the tang and held in place thereon with the stock in longitudinally stretched condition and with all parts of the 20 interior wall surface of the cavity in contact with the tang, to place the stock and the base portions of the individual teeth under tension in a direction longitudinally of the brush to maintain said teeth in stable equilibrium. 25

2. A dental brush comprising a handle having a tang, in combination with a hollow resilient and flexible stock having a cavity extending longitudinally thereto from one end thereof to a point adjacent the opposite end of the stock, 30 with longitudinally adjacent rows of juxtaposed wedge shaped teeth integral with one side of the stock, the cavity in said stock being normally of lesser length than the length of the tang and of lesser cross sectional area than the tang and the stock being drawn upon the tang and held in place thereon with the stock in longitudinally stretched condition, to place the stock and the base portions of the individual teeth under tension 35 in a direction longitudinally of the brush to maintain said teeth in stable equilibrium, the 40 cavity in the stock being completely filled by the tang. 45

DANIEL R. COLEMAN.
